FIG. IV

STANLEY M. UDALE,
WALTER S. ANDERSON
INVENTORS

BY *Stanley M. Udale*

ATTORNEY.

UNITED STATES PATENT OFFICE.

STANLEY M. UDALE AND WALTER S. ANDERSON, OF DETROIT, MICHIGAN, ASSIGNEES
TO EARL HOLLEY, OF DETROIT, MICHIGAN.

DIE STRAIGHTENER.

Application filed January 19, 1923. Serial No. 613,682.

To all whom it may concern:

Be it known that we, STANLEY M. UDALE and WALTER S. ANDERSON, citizens of the United States, residing at 893 Lothrop Ave. 5 and 1602 Parkview Ave., Detroit, in the county of Wayne and State of Michigan, have invented certain new and useful Improvements in Die Straighteners, of which the following is a specification.

10 This invention relates to an improved metal mold and specifically provides means whereby the mold may be adjusted after it has been heated to take care of distortion.

Figure I shows, in elevation, the mold and support.

Figure II shows a cross sectional elevation on the plane X—Y.

Figure III shows a cross sectional elevation on the plane U—V.

20 Figures IV, V and VI show alternative constructions.

Figure IV shows, in elevation, the mold and support.

Figure V shows a cross sectional elevation on the plane W—W.

Figure VI shows a cross sectional elevation on the plane Z—Z.

Description.—In Figures I, II and III, A is a hollow mold, B is a slot extending 30 through the rear and side walls of A, the purpose of which will be described later, C is a support to which the mold A is bolted by means of the set screws D, E, F, G, which are in tension. H, I, J, K, L, 35 M, N, O are set screws provided for the purpose of adjusting the mold by applying pressure against the rear of the mold.

In Figures IV, V and VI, P is the hollow mold, Q is a slot extending through 40 the rear and side walls of P, T is the mold support, R is a bolt clamping the mold P to the support T, this mold being always in tension. S, S', S'', S''' are four adjusting set screws which apply a pressure to 45 the rear of the hollow mold to balance the tension in the central bolt R.

Adjustment.—The adjustment, in Figures I, II and III, of the mold is as follows: When the mold is in use the working sur-

face of the mold A becomes hot and the 50 rear surface tends to remain relatively cool so that the working surface of the mold A becomes convex. To avoid leaky molds it is necessary to counter-act this tendency of the working face of the mold A to become convex by adjusting the set screws H, I, J, K, L, M, N, O. By reason of the slot B the mold A is sufficiently flexible to yield to the pressure exerted by the set screws so that the distortion due to the 60 unequal heating of the mold can be taken care of by this simple means.

In Figures IV, V and VI, the bolt R applies a pull on the center of the mold and the set screws S, S', S'', S''' apply a 65 corresponding and equal thrust. The result is that the tendency of the mold to become concave is neutralized and the mold can be held true by merely adjusting the four set screws S, S', S'', S''' and exerting a pull 70 on the central bolt R.

If a leak develops during actual operation a half turn on the bolt R will immediately check the leak and permit the operation to continue.

75 What we claim is:

1. A hollow mold adapted to receive molten metal, having a molding surface, a rear wall and four side walls, a slot extending through the rear wall and two side 80 walls, a mold support, bolts clamping the mold to said support, set screws for counter-acting the distortion of the molding surface.

2. A hollow mold adapted to receive molten metal, having a molding surface, a rear wall and two side walls, a slot extending through the rear wall and the two side walls, a mold support, one central tension bolt in said mold support, a plurality 90 of set screws whereby pressure is applied at a plurality of points on the rear of the hollow mold to counteract the distortion of the molding surface.

In testimony whereof we affix our signatures.

STANLEY M. UDALE.
WALTER S. ANDERSON,
